HEAT RESPONSIVE ALARM CABLE

Frank W. Jackson and Harry M. Nacey,
Chicago, Ill.

Application August 14, 1947, Serial No. 768,598

1 Claim. (Cl. 200—143)

1
The invention relates generally to electrical cables, and more particularly to a heat responsive cable for actuating fire alarm circuits, sprinkler circuits and the like.

In the past, heat responsive cables have been employed, embodying two conductors insulated from one another under normal conditions, the construction being such that upon the application of a predetermined amount of heat to the cable the insulation is broken down and a connection established between the two conductors, whereby electrical connections are established to operate the alarm or other device. An example of such a type of cable is disclosed in United States Letters Patent to W. G. Holmes, No. 2,185,944, wherein one or both conductors are formed from spring material such as spring or piano wire, the electrical connection between the two conductors upon the application of heat thereto being obtained from the inherent resiliency of the conductor or conductors which are twisted around one another to produce a pinching action therebetween. It will be apparent that the utilization of spring material results in a cable that is stiff and thus relatively difficult to work with as well as being comparatively expensive to manufacture. Likewise, the electrical connection obtained between the conductors is merely one of contact, again resulting from the inherent resiliency of the conductor or conductors.

The present invention has among its objects the production of a heat responsive cable in which ordinary copper or other pliable common types of conductors, may be employed in the manufacture of the cable so that the resulting cable is relatively pliable, and easily spliced and soldered to greatly facilitate installation. Also, if desired other conductors of non-ferrous or non-corrosive metals may be employed.

Another object of the invention is the production of such a cable in which the operation thereof is not dependent upon the resiliency of the conductors, and in which a direct connection may be made between conductors on the application of heat, as distinguished from merely a contact connection.

A further object of the invention is the production of such a cable which may utilize standard electrical materials so that the same is relatively inexpensive to manufacture, and improved operating conditions as to length of lines, voltages and current may be obtained.

Many other objects and advantages of the construction herein shown and described will be obvious to those skilled in the art from the disclosure herein given.

To this end our invention consists in the novel construction, arrangement and combination of parts herein shown and described, and more particularly pointed out in the claim.

In the drawing, wherein like reference characters indicate like or corresponding parts:

2
Fig. 1 is a diagrammatic view of a simple alarm system utilizing the present invention;

Fig. 2 is a plan view of a cable embodying the present invention with portions of the insulation and other elements broken away to disclose the construction thereof;

Fig. 3 is a sectional view through the cable illustrated in Fig. 2 taken approximately on line 3—3 of Fig. 2;

Fig. 4 is a sectional view similar to Fig. 3 of a modified form of the invention; and

Fig. 5 is a sectional view similar to Fig. 3 of another modified form of the invention.

The present invention contemplates the use of two ordinary wire conductors of copper or other suitable material which is relatively pliable, the conductors being electrically insulated from one another by suitable insulating material which is responsive to the application of heat, whereby the insulation will break down, in combination with a fusible electrically conducting material such as solder or the like. Thus, upon the application of heat to the cable the insulation will break down and the electrically conducting material will fuse to provide a direct electrical connection between the two conductors at the point of the insulation break down.

Referring to Fig. 1, 1 indicates generally a section of cable embodying the present invention having two conductors 2 and 3 therein, the conductor 2 in the present instance being connected to one side 4 of an alarm bell 5 or the like, and the conductor 3 operatively connected by a conductor 6 to one side of a battery 7, the opposite side of the battery being connected by a conductor 8 to the other side 9 of the alarm bell 5. Thus, as the conductors 2 and 3 are normally insulated from one another the bell circuit may be open, but upon application of heat to the cable and an electrical connection made between the conductors 2 and 3 thereof, the circuit will be closed to actuate the bell 5.

As illustrated in Figs. 2 and 3, the conductors 2 and 3 of the cable 1 may be twisted together, either one or both being twisted relative to the other, the conductor 2 being provided with a coating of insulation 11. The coating 11 may be of any suitable electrically non-conducting material having the desired heat characteristics, of which there are numerous types including rubber, cellulose, etc. We have found that cellulose compositions, as for example ethyl cellulose lacquer is suitable for the purpose, which is coated upon the wire in a sufficient thickness to provide the desired insulation. The conductor 3 is loaded or covered with a fusible metal solder 12, the two conductors being covered, if desired, by a suitable woven sheath 13. The coating of insulation 11 on the conductor 2 and the fusible metal 12 on the conductor 3 are both so selected that their heat responsive characteristics are approximately the same so that the insulation material will break down and expose the conductor 2 at

substantially the same temperature that the conducting material 12 will fuse and flow between the two conductors, thus electrically connecting the same and closing the alarm or other circuit. Thus, by proper selection of these materials cables of various critical heat responsive characteristics may be obtained, whereby the circuits may be closed for example, at 160° or 212°, etc. It will be noted that while the electrical connection between the two conductors may be by contact, a direct connection is made by the flowing of the fusible metal between the two conductors, consequently such connection is not dependent upon inherent resiliency of the conductors.

While the cable will function very satisfactorily without an additional sheath 13 enclosing the two conductors, we prefer to employ the sheath 13, making the same from a suitable material having greater heat resistance than the insulating material 11 or the conducting material 12, whereby the sheath will withstand higher temperatures than that required for breaking down of the insulating material and fusing of the conducting material, whereby the sheath will securely hold the conductors in position as well as forming a receptacle for the fused conducting material and retain the same adjacent the two conductors and maintain the electrical connection therebetween.

While the construction thus far described discloses the insulating material and the fusible conducting material on different conductors, if desired, these materials could be carried by the same conductor, such a construction being illustrated in Fig. 4 wherein the conductor 21 is provided with a coating of fusible conducting material 22 over which is a layer of insulating material 23, the conductor 24 being bare and a sheath 25 enclosing the two conductors. This form of cable will function in the same manner as previously described, for the construction illustrated in Figs. 2 and 3, the insulation 23 breaking down upon the application of the required amount of heat followed by the fusing of the conducting material 22 to establish electrical connection between the conductors 21 and 24.

In manufacturing this construction, if the insulating material and fusible conducting material are to respond to approximately the same degree of heat, the insulation may be applied by some other manner than dipping, as for example, by helically winding a sheet strip of insulation material about the conductor and its coating of fusible conducting material.

In the modified form of the invention illustrated in Fig. 5, the conductor 31 is provided with a coating of insulation 32, this conductor and its insulation coating being substantially identical with the conductor 2 and corresponding insulation 11, while the conductor 33 is bare. Extending along the two conductors is a strip or ribbon 34 of fusible conducting material which with the two conductors is enclosed in an outer sheath 35, and while the cross sectional shape of the ribbon 34 is illustrated as circular, obviously it may be of some other suitable shape. The operation of this cable likewise will be substantially the same as that described for the other constructions, the insulation 32 breaking down upon the application of the required amount of heat followed by the fusing of the strip 34 and the electrical connection of the conductors 31 and 33 thereby. It will be noted that while fusible metals employed in heat responsive devices such as this may be quite brittle and thus rendered unsatisfactory for

use as a conductor due to possible breakage during installation, etc., breakage of the fusible metal strip 34 would be immaterial insofar as the construction illustrated in Fig. 5 is concerned as the strip 34 does not function as a conductor, consequently breakage thereof would have no effect on the operation of the device and any broken segments would be held in position by the sheath 35 and a supply of material extending throughout the length of the cable at all times. The fusible element could also be formed in some cases as a strip of sheet material and helically wrapped around both conductors.

It will be noted that all of the constructions described include two conductors operatively insulated from one another in combination with a fusible conducting material operative to flow between and electrically connect the two conductors upon the break down of the insulation and fusing of the conducting material; likewise that conductors of higher electrical efficiency than a steel conductor may be employed.

It will be noted from the above description that we have provided a heat responsive cable, which may be formed of generally standard materials and which is relatively pliable to facilitate installation. Likewise, it will be noted that the present construction provides a direct connection between conductors by a suitable conducting material associated therewith independent of inherent resiliency of one or both of the conductors.

Having thus described our invention, it is obvious that various immaterial modifications may be made in the same without departing from the spirit of our invention; hence we do not wish to be understood as limiting ourselves to the exact form, construction, arrangement and combination of parts herein shown and described, or uses mentioned.

What we claim as new and desire to secure by Letters Patent is:

In a heat responsive cable, the combination of a pair of relatively soft, pliable conductors of approximately equal diameter, at least one of said conductors being twisted around the other, one of said conductors having a coating of a fusible, electrically conducting material thereon and the other conductor having a coating of insulation thereon, said insulation being formed of a material which will break down in response to heat to permit said conducting material upon fusing to flow between the conductors and electrically connect the same, and a sheath enclosing all of the respective elements formed from a material requiring greater temperatures for breakdown than said insulation or fusible conducting material.
